UNITED STATES PATENT OFFICE.

JOHN P. ODGERS, OF PHILADELPHIA, PENNSYLVANIA, ASSIGNOR TO THE
A. M. COLLINS MANUFACTURING COMPANY, OF SAME PLACE.

DESIGN FOR A PHOTOGRAPHIC MAT OR MOUNT.

SPECIFICATION forming part of Design No. 31,581, dated October 3, 1899.

Application filed August 8, 1899. Serial No. 726,592. Term of patent 7 years.

To all whom it may concern:

Be it known that I, JOHN P. ODGERS, a citizen of the United States, residing in Philadelphia, Pennsylvania, (my post-office address being 527 Arch street,) have invented and produced a new and original Design for a Photographic Mat or Mount, of which the following is a specification.

My design for a photographic mat or mount is fully illustrated in the accompanying drawing, the figure of which represents a face view illustrating the design.

The essential feature of the design is the border of oval shape, made up of a series of figures gradually increasing in size from small figures at the top and bottom of the border to larger figures at each side of the same. The border is made up of a series of rosettes *a*, having small dashes *b* between them, the

rosettes at the top and bottom of the border *20* being small, while those at each side are larger. The rosettes increase in size gradually from the top and bottom of the border to the sides of the same, giving the effect clearly illustrated in the accompanying drawing. *25*

I claim—

The design for a photographic mat or mount as herein described and as shown in the accompanying drawing. *30*

In testimony whereof I have signed my name to this specification in the presence of two subscribing witnesses.

JOHN P. ODGERS.
